[57] **CLAIM**

The ornamental design for a cliplead electrode for use
in attaching electronic apparatus to an animal's skin,
substantially as shown and described.

DESCRIPTION

FIG. 1 is a front perspective view of a cliplead electrode
for use in attaching electronic apparatus to an
animal's skin showing my new design the cliplead electrode
being in an open position;

FIG. 2 is a front elevational view thereof the cliplead
electrode being in a closed position; and

FIG. 3 is a right side elevational view thereof, the clip-
lead electrode being in a closed position.
